UNITED STATES PATENT OFFICE.

ISIDOR KITSEE, OF PHILADELPHIA, PENNSYLVANIA, ASSIGNOR OF ONE-HALF TO WILLIAM J. LATTA, OF PHILADELPHIA, PENNSYLVANIA.

TELEPHONY.

No. 388,507.

Specification of Letters Patent. Patented May 26, 1908.

Application filed April 25, 1904. Serial No. 204,858.

To all whom it may concern:

Be it known that I, ISIDOR KITSEE, of the city and county of Philadelphia, State of Pennsylvania, have invented certain new and useful Improvements in Telephony, of which the following is a specification.

My invention relates to an improvement in telephony and has more special reference to telephonic transmission with one line not directly grounded.

In my experiments with telephonic transmission over comparative long distances and over lines in which artificially all conditions of long lines were reproduced, I found that if 15 a device consisting of two coils, such for instance as an inductorium, is connected with one coil to the line and with the second coil to the ground, either at one or both ends of the line, the sound could be distinctly heard.

Having established such lines and having 20 established communication through such lines, I found that the interferences usually accompanying lines metallically grounded are also to a more or less degree present if the 25 lines are grounded only inductively. In places, such as large cities, wherein through the running of electric cars with rails as return, stray currents are encountered, and where other sources of current greatly affect 30 grounded wires, it is necessary to counteract these earth currents and to do so, I have recourse to an arrangement whereby these ground influences are neutralized in a manner so that they shall not encumber the line.

Referring to the drawing: Figures 1 and 2 are diagrammatic views embodying my invention; Fig. 1 illustrates diagrammatically two stations connected together with one line and Fig. 2 represents diagrammatically 40 the windings of the two coils of which the inductorium consists.

In Fig. 1; A and A¹ are two stations inductively connected together through the line B; the terminals of said line are connected through wire C with one pole of the receiver D and the other pole of said receiver is connected through wire E with one terminal of the helix F, the other terminal of 45 said helix remaining free. In this helix is inserted the electro-magnetic coil G ground- 50 ed with one terminal at I through the wire H; the second terminal of said coil remaining free.

In Fig. 2, F and G are the helix and 55 electro-magnetic coil respectively. The elec-

tro-magnetic coil G consists of the two parts g and g¹, wound in opposite direction to each other. A current, therefore, entering this coil will induce in the helix impulses in accordance with the direction of the convolutions of said coil, and as one half of said convolutions are wound from right to left and the other half of the convolutions wound from left to right, it is obvious, that the impulses induced through said coil in F will be 60 partially in one and partially in an opposite direction, thereby neutralizing each other. This function of a coil wound as illustrated in Fig. 2 is so well understood by persons versed in the art that it is unnecessary for 65 me to go more into the detail of the principle whereon this function is based; it suffices to state, that in the windings of these coils care should be taken that the inductive influence of the same on the helix in which they are 70 inserted should be perfectly neutralized, and it is best to make these coils in a manner so that the same can easily be removed, or partially withdrawn; for I have found that even if the coils consist of two halves, exactly 75 alike and electrically connected together but wound in opposition as to each other, and the whole arrangement inserted in a line as illustrated, a source of interrupted current still causes slight disturbances in the re- 80 ceiver D and it is often necessary to withdraw that end of the coil which is connected to the line H partially out of the helix, so that the inductive influence of the opposing coil should be greater than the inductive 85 influence of that part which is connected to the ground.

I have illustrated the inductorium as consisting of two coils, the helix F and the electro-magnetic coil G and I have illustrated 90 the electro-magnetic coil G as consisting of two parts wound in opposition to each other for the purpose of neutralizing the inductive effect of the impulses flowing therein, but it is obvious that instead of the electro-magnetic coil G, the coil of the helix F may consist of two parts wound in opposition to each other and in that case the coil of G may be wound in the usual manner without opposing parts. The effect in both cases would be 95 the same.

Having now described my invention, what I claim as new and desire to secure by Letters Patent is:—

1. In telephony, means to neutralize earth 100

currents in a line of transmission, said means comprising an inductorium, one coil connected to the line of transmission, the second coil connected to the ground; one of said 5 coils constructed so that one part has an inducing effect opposite to the inducing effect of the second part.

2. In telephony, a line of transmission, two stations therefor, each station equipped 10 with necessary transmitting and receiving devices, the terminals of said line connected to one coil of a converter, the second coil con-

nected to the ground, one of said coils constructed in a manner, so that one part is neutralized by the remaining part of same. 15

In testimony whereof, I hereby sign my name in the presence of two subscribing witnesses, this twenty-third day of April, A. D. 1904.

ISIDOR KITSEE.
